Specification for Design.

Patented Mar. 4, 1919.

Application filed February 6, 1918. Serial No. 215,706. Term of patent 7 years.

To all whom it may concern:

Be it known that I, EMMA W. BOSKOWITZ, a citizen of the United States, residing at Watts, in the county of Los Angeles and State of California, have invented a new, original, and ornamental Design for Clothes-Hangers, of which the following is a specification, reference being had to the accompanying drawings, forming a part thereof.

I claim:

The ornamental design for a clothes hanger, as shown.

EMMA W. BOSKOWITZ.
